United States Patent Office

Des. 227,663
Patented July 10, 1973

227,663

DOMED BUILDING

James F. Garufo, Max W. Snodgrass, Guy M. Shelley,
Jr., and George C. Christopher II, Wichita, Kans., as-
signors to Aerodome Industries, Inc., Wichita, Kans.

Filed Dec. 17, 1971, Ser. No. 209,483

Term of patent 14 years

Int. Cl. D25—03

U.S. Cl. D13—1 E

Fig. 1.

FIG. 1 is a top plan view of a domed building showing our new design;

FIG. 2 is a front elevational view thereof; and

FIG. 3 is a side elevational view thereof.

We claim:

The ornamental design for a domed building, as shown.
